UNITED STATES PATENT OFFICE.

ALBERT L. REINMANN, OF PITTSBURG, PENNSYLVANIA.

VALVE-CASE FOR MERCURIAL AIR-PUMPS.

SPECIFICATION forming part of Letters Patent No. 331,546, dated December 1, 1885.

Application filed September 24, 1885. Serial No. 177,967. (No model.)

To all whom it may concern:

Be it known that I, ALBERT L. REINMANN, residing at Pittsburg, in the county of Allegheny and State of Pennsylvania, a citizen 5 of the United States, have invented or discovered certain new and useful Improvements in Valve-Cases for Mercurial Air-Pumps, of which improvements the following is a specification.

10 In the accompanying drawings, which make part of this specification, Figure 1 is a sectional elevation of a length of pipe forming part of a mercurial air-pump, said pipe having valve-chambers for the reception of 15 float or automatically-acting valves. Fig. 2 is a similar view showing certain modifications in the shape of the valve-chamber and the contained valve. Figs. 3, 4, and 5 are views showing different forms of valves in ele- 20 vation.

In making these valve-chambers it is customary to enlarge a portion of the pipe in which said chambers are to be formed, and then after inserting the valve to draw down 25 the pipe at each end or side of the enlargement to the normal or desired size of the pipe, thus inclosing the valve in a chamber having walls integral with the pipe at each side thereof. This construction is objection- 30 able, for the reason that if the contained valve is broken or injured in any way it is necessary to remove all that portion of the pipe in which the valve-chamber is located, and substitute therefor an entirely new length of pipe, 35 thus adding considerably to the cost of operating the pump.

The object of my invention is to so construct such portions of mercurial pumps as to include chambers in their length as to permit 40 of the ready insertion and renewal of the valves without destroying the chamber in which the valve is located; and to this end my invention consists in the construction of parts, all as more fully hereinafter described 45 and claimed.

In carrying out my invention the pipe is made in sections 1, 2, and 3, as shown, the length of such sections being determined by

the location of the valve-chambers. The adjacent ends of two adjoining sections are 50 then enlarged, as at 4, 5, 6, and 7, for the reception of the valve 8, the pipe at the ends of the enlargements being contracted, as shown. The outer ends of the enlargements of two sections are made of such relative diameters that the end of one will fit within 55 the end of the other, the ends being correspondingly tapered in order that they may be ground together, thereby making a hermetic joint. 60

In a mercurial pump having the valve-chamber constructed as described the valves are not put in place until the parts of the pump are placed together, thus avoiding any liability of breaking the valves in handling, 65 the pipe-sections having the valve-chambers integral therewith.

Another important advantage arising from the above-described construction of valve-case is the possibility of inserting a tool with- 70 in the enlargement for the purpose of properly shaping the valve-seats at the ends of the enlarged portions, and also of properly shaping and sizing the enlarged cavity to suit the kind of valve to be inserted in the chamber. The valves used in these chambers are varied as to shape and size, as shown, and are adapted to close the opening at either end of the chamber, as desired. 75

The valves employed in closing the lower 80 end of the valve-chamber are preferably made hollow for the reception of a small quantity of mercury, which, from its weight, will seat the valve before all the mercury can escape from the valve-chamber, the mercury caught 85 in the chamber by the seating of the valve serving as a seal.

The desired amount of mercury may be sealed in the hollow valves, if desired; or an opening, 9, may be formed in the side of the 90 valve, the mercury filling the valve through said opening as it fills the valve-chamber.

It will be noticed that in the above-described construction of valve-case the valve and valve-seat may be ground together for the 95 purpose of producing a perfectly-tight joint

between them, and that the case can be easily taken apart for the purpose of cleaning the case-valve.

I claim herein as my invention—

5 In a mercurial air-pump, a valve-case consisting of the enlarged ends of adjoining sections of pipe forming a part of the pump, said enlarged ends fitting one within the other, in

combination with a valve located within said case, substantially as set forth.

In testimony whereof I have hereunto set my hand.

ALBERT L. REINMANN.
